US00D607028S

(12) **United States Design Patent**
Subilia

(10) **Patent No.:** **US D607,028 S**
(45) **Date of Patent:** **** Dec. 29, 2009**

(54) **WATCH WINDING MECHANISM**

(75) Inventor: **Philippe Subilia**, Lausanne (CH)

(73) Assignee: **Ideò Tempo SA**, Lausanne (CH)

(**) Term: **14 Years**

(21) Appl. No.: **29/317,059**

(22) Filed: **Apr. 22, 2008**

(30) **Foreign Application Priority Data**

Oct. 22, 2007 (WO) DM/069 447

(51) **LOC (9) Cl.** **15-99**

(52) **U.S. Cl.** **D15/199**

(58) **Field of Classification Search** D15/199;

81/7.5; 366/14; 368/10, 206-209

See application file for complete search history.
